UNITED STATES PATENT OFFICE.

JOHN GEORGE ROBINSON AND ROBERT ABSALOM THOM, OF FAIRFIELD, MANCHESTER, ENGLAND.

STEAM SUPERHEATER.

Application filed September 27, 1920. Serial No. 413,070.

To all whom it may concern:

Be it known that we, JOHN GEORGE ROBINSON and ROBERT ABSALOM THOM, subjects of the King of Great Britain and Ireland, respectively residing at Fairfield, Manchester, in the county of Lancaster, England, whose post-office addresses are, respectively, "Mere Bank," Fairfield, and 11 Leven Terrace, Fairfield aforesaid, have invented Improvements in Steam Superheaters; and we do hereby declare the following to be a full, clear, and exact description of the invention, such as will enable others skilled in the art to which it appertains to make and use the same.

This invention relates to improvements in steam superheaters for boilers of the multiple smoke or fire tube type.

This invention consists in the novel construction and combination of the parts hereinafter fully described and claimed, and which are specially applicable to marine boilers used on sea going vessels, which boilers are provided with superheaters having vertically arranged headers.

In the drawings,

Fig. 1 is an elevation showing smoke tubes of two nests of such tubes of a marine boiler, with a header, superheater elements and flange block connections securing the ends of the elements to opposite side walls of the header according to one embodiment of the invention, some of the smoke tubes and superheater elements being omitted from the group to the left of the header for convenience in illustration.

Fig. 2 is a sectional plan view of the superheater illustrated in Fig. 1.

Fig. 3 is a longitudinal section of the header taken on the line A—B Figs. 1 and 2 looking in the direction of the arrow.

Fig. 4 shows detail views of one of the flange blocks in which the steam inlet and outlet ends of an element are fixed and by which the element is secured in a steam tight manner to the header as hereinafter described, the left hand view being a central longitudinal section of the block.

Fig. 5 is a side elevation of a portion of the header shown in Figs. 1, 2, and 3, with the ends of the superheater elements secured thereto.

Figs. 6, 7 and 8 are views showing the construction and arrangements hereinbefore mentioned, including the bending of the end

portions of the elements situated in the uptake and extending to the header wall, whereby any individual element can be disconnected from the header and removed from the smoke tubes without disconnecting or in any way interfering with any other element. Of these views Figs. 6 and 7 are views similar to Figs. 1 and 2 except that the left hand nest of boiler smoke tubes and their superheater elements have been omitted for convenience in illustration; and Fig. 8 is a side elevation of the header shown in Fig. 6 with the ends of the elements secured thereto, and also shows, in section, some of the boiler smoke tubes and portions of the U-pipes of the elements therein.

Fig. 9 is a transverse section of an alternative form of header hereinafter referred to.

Like reference numbers indicate corresponding parts in the several figures of the drawings.

Referring to the drawings, 1 is the header, preferably a steel casting, divided by the internal partition or wall 2, extending uniformly from end to end of the header, into two simple steam chambers 3 and 4 (see Figs. 2 and 3) respectively for saturated steam and superheated steam, saturated steam being conveyed into the chamber 3 through the opening 5 in the top of the header to which the steam pipe from the boiler is connected by a suitable flanged connection as usual, 6 being the opening in the top of the header through which superheated steam passes from the chamber 4 into the steam delivery pipe leading to the engine this latter pipe being also connected to the top of the header by a suitable flange as usual. 7 (Figs. 1 and 3) is a plate closing the lower ends of the steam chambers 3 and 4 this plate 7 being suitably secured to the lower end of the casting for instance by a suitable number of studs fixed in the casting and having nuts 8 screwed up on their ends which project through holes in the plate 7. 9 are flanges or forward projections forming in effect continuations of the side walls of the header to which the ends of the superheater elements are secured as hereinafter described.

In the application of the invention to a superheater for a marine boiler as illustrated, the saturated steam inlet and superheated steam outlet ends of the superheater

elements appertaining to the nests of smoke tubes situated on either side of the header 1 are secured to opposite side walls of the header in registration with suitably spaced holes in these walls, the hole for the saturated steam inlet end and that for the superheated steam outlet end of an element being arranged one behind the other in a plane transversely of the header as shown 5 at 10 and 11 Figs. 2 and 3, the holes 10 communicating with the saturated steam chamber 3 and the holes 11 communicating with the superheated steam chamber 4. In the example illustrated the steam inlet and outlet ends of each superheater element are fixed in a flange block or plate 12 in holes provided one behind the other in the longitudinal central plane of the block and these flange blocks 12 lie transversely of the header when in position securing the ends of the elements to the opposite side walls of the header as clearly shown in Figs. 2 and 3 of the drawings. As shown in Figs. 2 and 3 the holes in each flange block 12 which receive the screw devices 13 and 14, by which the blocks with element ends are secured to the header wall, also lie in the central longitudinal plane of the block, these screw devices and the hereinbefore mentioned holes 10 and 11 in the header wall therefore lying in the same plane transversely of the header as shown in Figs. 2 and 3. As shown more clearly in Figs. 2 and 4 each flange block 12 has formed in it a hole 15 which receives the screw device 14 for securing the block at the front of the header, and an open ended slot 16 which receives the screw device 13 for securing the end of the block at the rear of the header as shown in Fig. 2. The screw devices 13 are, as in the example illustrated, preferably screw studs screwed at their inner ends into the header casting and having fastening nuts 17 screwed up on their outer ends which project a suitable 40 distance beyond the outer side or face of the flange block, and the screw devices 14 are T-bolts having fastening nuts 17^a screwed up on their outer ends which project a suitable distance beyond the outer side or face of the flange block 12, the stems of these bolts 14 extending through suitable holes (or they might be open ended slots) in the flanges or projections 9 on the header walls which flanges form abutments for the T-heads 17^b of these bolts. It will be seen that the outer faces of the walls of the header to which the flange blocks 12 are secured and the inner faces of these blocks are plain faces, and these faces are suitably machined so as to ensure an effective steam tight joint. As clearly shown in Fig. 2 the internal partition wall 2 of the header is of curved form or has approximately the form of an inverted trough in cross section. By this

construction the over-all width of the header from side to side and the overall depth of the header from rear to front are made as small as possible, while the cross areas of the saturated and superheated steam chambers 3 and 4 respectively are equal or substantially equal to each other, the cross area of the chamber 3 being equal or substantially equal to that of the usual steam pipe which conveys saturated steam from the boiler to the chamber 3 and the cross area of the chamber 4 equal or substantially equal to that of the usual steam pipe which conveys superheated steam from the chamber 4 to the engine. Further with this construction it is possible to employ the hereinbefore flange blocks with the ends of the elements fixed therein as close to each other as practicable and the screw devices 13 and 14 as close as practicable to the ends of the elements whereby a very effective steam tight jointing of the ends of the elements to the header is obtained. The header casting is also very simple to manufacture, comparatively cheap and light. As shown in Figs. 1 and 3 the flange blocks 12 on the saturated steam inlet and superheated steam outlet ends of each set of superheater elements appertaining to smoke tubes in two adjacent lateral rows of smoke tubes are arranged in a group there being, in this example, three flange blocks in each group corresponding to the number of elements in the set, the flange blocks in each group being arranged in close proximity to each other and the several groups of flange blocks suitably spaced apart as shown. Although only two flange blocks 12 are shown as applying to superheater elements in the smoke tubes of two rows in the nest of tubes situated to the left of the header 1 in Fig. 1 it will be understood that, for convenience in illustration, one element with its smoke tubes has been omitted from each set in this nest of smoke tubes.

The expression "set of superheater elements" used in the preceding paragraph is intended to relate to several elements each of which has its U-pipes extending into smoke tubes contained in two adjacent rows of smoke tubes.

In the example illustrated, referring to the smoke tubes situated to the right of the header 1, Fig. 1 there are three superheater elements in each set and each of these elements has six U-pipes three of which extend into three smoke tubes in one lateral row and three into corresponding smoke tubes in the next row, the end portions of these elements being bent and extending into the smoke box or uptake so that the flange blocks 12, fixed on the saturated steam inlet and superheated steam outlet ends of these bent portions, will when the elements are inserted in the smoke tubes lie against

the wall of the header to which they are to be secured by the hereinbefore mentioned screw devices 13 and 14 with nuts 17, 17^a respectively. Inasmuch as in the example 5 illustrated the several sets of elements are identical a description of the elements of one set and of the method of securing the steam inlet and outlet ends of these elements to the header will be sufficient. The nuts 17^a, as 10 shown, are box nuts, and the outer screwed ends of the T-bolts 14 terminate at a suitable position within these nuts.

Referring to the set of elements appertaining to the smoke tubes in the first two 15 lateral rows of such tubes it will be seen that the first element which occupies the group of six smoke tubes nearest the header is so formed and arranged that its saturated steam inlet and superheated steam outlet end 20 portions, marked respectively 18 and 19, at the points where they connect with the respective U-pipes 18^a, 19^a are at the maximum distance apart while at the points where their steam inlet and outlet ends 10^a, 25 11^a, Figs. 4 and 5 are secured in the flange block 12 they lie one behind the other in the same transverse plane of the header, the said flange block itself lying in the central horizontal plane between the said two rows 30 of smoke tubes. In the case of the second superheater element of the set, namely that which occupies the next group of smoke tubes further from the header wall, it will be seen that the laterally bent portions 20, 35 21, Figs. 1, 2, and 5 of this element connect respectively with the U-pipes 20^a, 21^a in adjacent smoke tubes in one lateral row of smoke tubes (the upper row in the example shown) and lie one behind the other in the same or 40 substantially the same plane; and in the case of the third element of this set, i. e., the element occupying the group of smoke tubes still further from the header 1, the laterally bent portions 22, 23 of this element connect 45 respectively with or form continuations of the U-pipes 22^a, 23^a in adjacent smoke tubes in the next or lower lateral row of smoke tubes, and also lie one behind the other in the same or substantially the same plane. 50 Also as shown the flange blocks 12 in which the saturated steam inlet and outlet ends of these second and third elements of the set are fixed are arranged one on either side of and in close proximity to the flange block 55 12 of the first element of the set.

24 Figs. 1, 2 and 5 indicates a box spanner which can be readily applied to the rear fastening nuts 17 of the upper and lower flange blocks 12 by which the ends of the 60 second and third superheater elements of a set are secured to the header, and 25, Fig. 5 indicates the tommy bar operating the box spanner 24, 26 (Figs. 1 and 2) being suitably spaced tommy holes in the spanner 24. 65 The spanner 24 as shown is without the

usual operating stem or spindle. 27 indicates a box spanner having an operating stem 28 and tommy holes 29 applied to the rear fastening nut 17 of the intermediate flange block 12 by which the ends of the 70 first element of the set are secured to the header. It will be understood that the spanners 24 and 27 can be readily applied to the nuts 17 of the respective flange blocks (above referred to) by being passed in between the end portions of the element pipes situated in the smoke box or uptake. Either of the box spanners 24 or 27 can of course be employed for the forward fastening nuts 75 17^a of the flange blocks. 80

Referring to Figs. 6, 7, and 8 of the drawings these figures show how, by forming the end portions 20, 21, of the second element of a set with suitable bends, indicated at 30, 31, Figs. 6 and 8 and the end portions 22, 23 of the third element of the set with similar bends indicated at 32, 33, so that these portions lie to one side and clear of the U-pipes of the elements in the respective rows of smoke tubes, any one element of a set can, 90 when the fastening nuts of its flange block 12 have been loosened or removed, be removed from the boiler smoke tubes without in any way disturbing any other element, including its flange block connection to the 95 header, and this can be done with the boiler smoke tubes pitched equally on a vertical plane, i. e., it is not necessary to increase the pitch of the smoke tubes on the vertical plane as between the sets of elements. The 100 bending of the end portions of the first element of a set (i. e., the element nearest the header 1), whereby effective clearance is given in respect of the inner fastening nut 17 for the flange block 12 of this element, 105 is indicated at 34 in Fig. 8. The bending of the respective elements of the set as above described is identical for each set of elements. 110

35 indicates the suitably pitched smoke tubes of the boiler.

36 is a box spanner shown in position between the pipes 21 and 18 for tightening or slackening the rear nut 17 of the upper flange block 12 belonging to the second element of a set. The box spanner 36 is also shown in position between the pipes 18 and 19 and in engagement with the nut 17 of the intermediate flange block 12 of the first element of a set, and the spanner is also shown 115 in position between the pipes 19 and 23 and in engagement with the nut 17 of the lower flange block 12 of the third element of a set. This illustrates how the box spanner can be readily applied and operated for tightening 120 or slackening any of the rear nuts 17 of the flange blocks 12 belonging to the several sets of superheater elements. As the pipes 21 and 18, 18 and 19, 19 and 23 respectively are not in the same vertical plane there is 125 130

ample clearance for the box spanner to be applied to the nuts 17, see Fig. 8.

Referring to Fig. 9, which shows an alternative form of the header 1, it will be seen that the partition wall 2' in this header is a plain flat wall instead of being curved or trough shaped as shown in Figs. 2, 3 and 7 of the drawings. The header with curved or trough shaped partition wall 2 as shown in Figs. 2, 3, and 7 is however, the preferable construction as it enables the over all width of the header to be kept as small as practicable while obtaining the required cross area of the steam chambers 3 and 4.

What we claim as our invention and desire to secure by Letters Patent is:—

1. In a superheater, a vertical header provided internally with a single imperforate partition plate which extends uniformly between its top and bottom and divides it into a front chamber and a rear chamber, said chambers having lateral openings in their side walls adjacent to the said partition plate, connecting blocks arranged transversely of the said partition plate and one above another and having inlet and outlet openings in their middle parts which are spaced to communicate with the corresponding openings of the chambers, said blocks having also front and rear openings in their end portions, superheater elements having their inlet and outlet end portions secured in the respective openings of the blocks, and

fastening devices engaging with the openings in the end portions of the blocks and securing each of the several blocks to the header independently of the others. 35

2. A superheater as set forth in claim 1, the said partition plate being channel-shaped in cross-section and arranged with its middle part projecting rearwardly of its ends in a vertical plane, and the said chambers being of substantially equal area in cross-section. 40

3. A superheater as set forth in claim 1, and having a forwardly projecting vertical flange formed of an extension of one of its side walls and provided with openings for the fastening devices at the front end portions of the said blocks. 45

4. A superheater as set forth in claim 1, the joints between the said blocks and the side wall of the header being formed of plane surfaces, and the ends of the superheater elements being arranged within the 55 openings of the said blocks, so that the blocks can be slid upon the joint surface of the header side wall in coupling and uncoupling the superheater elements.

In testimony whereof we affix our signatures, in presence of two witnesses.

JOHN GEORGE ROBINSON.
ROBERT ABSALOM THOM.
